HARROW CONSTRUCTION

Stephen M. Young, Hamilton, Ontario, Canada,
assignor to International Harvester Company,
Chicago, Ill., a corporation of New Jersey

Application September 14, 1940, Serial No. 356,766

14 Claims. (Cl. 55—83)

This invention relates to a harrow construction. More specifically it relates to a harrow construction of which both front and rear gangs may be angled jointly, and the rear gangs may be angled separately.

In harrow constructions it is desirable to have provision for joint adjustment of the front and rear gangs of a harrow as well as separate adjustment of the rear gangs.

An object of the present invention is to provide an improved harrow.

A further object is the provision of a tandem harrow of which the front set of gangs are adjustable jointly with the rear set and the one set may be adjusted independently of the other set.

Another object is the provision of a tandem harrow in which front and rear gangs may be adjusted jointly and the rear gangs may be adjusted separately.

According to the present invention an adjustable lever is mounted on the front frame of a tandem harrow. One end of the lever is connected to the front gangs of the harrow and the other end is connected to the rear gangs by an adjustable connection comprising a rod slidably engaging a tube.

In the drawings:

Figure 1 is a side elevation of one form of harrow embodying the present invention;

Figure 2 is a side elevation of a second form of harrow; and,

Figure 3 is a plan view of the harrow of Figure 1.

The form of harrow of Figures 1 and 3 comprises a front frame 10, a pair of front gangs 11 connected adjacent their outer ends to the front frame by means of straps 12 and 13, a rear frame 14, and rear gangs 15 connected adjacent their outer ends, as at 16, to the rear frame. The rear frame 14 is connected to the outer ends of the front gangs 11 by means of links 17 connected at 18 to the front gangs. Each link 17 comprises a lower member 19 passing beneath the front portion of the rear frame 14 and an upper member 20 secured at 21 to the lower member 19 adjacent its point of connection with a front gang 11 at 18 and passing over the rear frame 14 and having a slidable connection at its rear end in a member 22 forming part of the rear frame. The rear end of each lower member 19 is connected to an intermediate portion of the upper member 20 by means of a bolt 23 which also serves as a point of connection for one end of a link 24 connected in turn to a lever 25

pivoted at 26 to a front mid-point of the frame 14. The parts just described constitute a means by which the rear gangs of the harrow have a flexible connection with the front gangs and yet are made to follow directly behind the front gangs. This construction is claimed and described more fully in the copending application of Stephen M. Young, Serial No. 337,233, filed May 25, 1940.

As seen in Figure 1, a lever 27 is mounted at 28 on a horizontal pivot on the front frame 10. Links 29 connect the lower end of the lever 27 and the inner ends of the front gangs. A triangular framework 30 is connected at 31 to the upper end of the lever 27, and from this framework extends a rod 32 in telescoping relation within a tube 33. The tube 33 is slidably mounted in a tube 34 slidably supported by a strap 35 on the rear frame 14. A strap 36 is secured to the front end of the tube 34. Rods 37 connect the strap 36 and the inner ends of the rear gangs 15, as at 38. Forward movement of the tube 33 within the tube 34 is limited by a cotter pin 39 connected by a chain 40a to a cotter pin 40. The cotter pin may extend through tube 33 in a number of positions and, when not in use, may hang from chain 40a connected to tube 33 by cotter pin 40, which extends through tube 33 and is permanently connected thereto. The front end of the tube 33 carries a standard 33a, to which is pivotally connected a nut 41. A threaded crank 42 engages the nut 41 and is rotatably supported against axial movement in a collar 43 carried by the framework 30. The lever 27 carries a nut 44 which is engaged by a threaded crank 45 rotatably supported against axial movement in a collar 46 carried by a member 47 secured to the front frame 10 and braced by a member 47'.

Joint adjustment of the front and rear gangs is effected through rotation of the crank 45, which causes an angular movement of the lever 27. The lower end of the lever causes movement of the inner end of the front gangs through the links 29, and the upper end of the lever 27 causes movement of the inner ends of the rear gangs by means of the framework 30, the rod 32, the tubes 33 and 34, cotter pin 39 or 40, and the bent rod 37. In movement of the rear gangs from transport position to working position, in which the inner ends of the rear gangs extend forwardly, forward movement of the tube 33 effects a forward movement of the tube 34. In movement of the gangs from working position to transport position, rearward movement of the

tube 33 is without effect on the tube 34, and, accordingly, without effect on the rear gangs 15. Draft forces upon the rear gangs during forward movement of the harrow cause the inner ends of the rear gangs to be moved rearwardly into transport position. Separate adjustment of the rear gangs is had by rotation of the crank 42. As the crank is rotated, the nut 41 is adjusted axially of the crank and the sleeve 33 is moved along the rod 32, thus causing adjustment of the rear gangs.

By removal of the cotter pin 39 from the tube 33, movement of this tube either forwardly or rearwardly is completely without effect upon the tube 34. Consequently, the rear gangs may be kept in straightened or transport position through draft forces, and the front gangs are angled as desired, so that the harrow operates as an "out-throw" harrow. It may also be operated as an "in-throw" harrow with the front gangs in straight position, the cotter pin 39 inserted through the tube 33, as shown, and adjustment of the rear gangs to working position by means of the crank 42.

In the modification of Figure 2, the nut 41 and the threaded crank 42 of Figure 1 are replaced by a lever 48 pivotally connected to an arcuate sector 49. The arcuate sector is secured to a rod 50 connected at its forward end by a member 51 to the upper end of the lever 27 and extending in telescoping relationship in a sleeve 33. The lever 48 is connected to the sleeve 33 by means of a link 52 and a lug 52a secured to the sleeve 33. A detent mechanism 53 fixes the lever 48 to the arcuate sector 49. Joint adjustment of the front and rear gangs of the harrow of Figure 2 is had in the same way as with the harrow of Figure 1, that is, by rotation of the crank 45. Separate adjustment of the rear gangs is effected by an angular movement of the lever 48. Movement of the lever 48 causes a movement of the tube 33 along the rod 50 and a consequent movement of the rear gangs.

It will be apparent from the foregoing description that two modifications of a new and novel harrow construction have been provided in which there is joint adjustment of the front and rear gangs of a harrow and separate adjustment of the rear gangs, relative movement of a sleeve member over a rod forming part of the connection with the rear gangs. In the one modification, adjustment of the sleeve with respect to the rod is effected by rotation of a threaded crank which moves a nut secured to the sleeve along the crank. In the other modification, relative movement of the sleeve is effected by angular movement of a lever with respect to a sector. The intention is to limit the invention only within the scope of the appended claims.

What is claimed is:

1. In a harrow comprising a pair of front gangs, a front frame connected thereto, a pair of rear gangs, a rear frame connected thereto, the combination therewith of means connecting a frame and the front gangs for adjusting both front gangs jointly, means connecting a frame and the rear gangs for adjusting both rear gangs simultaneously, one of the aforementioned means including a pair of telescoping parts adjustably fixable with respect to one another, and means for operating the two aforementioned means simultaneously for joint adjustment of front and rear gangs.

2. In a harrow comprising a pair of front gangs, a front frame connected thereto, a pair of rear gangs, a rear frame connected thereto, the com-

bination therewith of means connecting a frame and the front gangs for adjusting both front gangs jointly, means connecting the same frame and the rear gangs for adjusting both rear gangs simultaneously, one of the aforementioned means including a pair of telescoping parts adjustably fixable with respect to one another, and means for operating the two aforementioned means simultaneously for joint adjustment of front and rear gangs.

3. In a harrow comprising a pair of front gangs, a front frame connected thereto, a pair of rear gangs, a rear frame connected thereto, the combination therewith of means connecting a frame and the front gangs for adjusting both front gangs jointly, means connecting the same frame and the rear gangs for adjusting both rear gangs simultaneously, said means including a pair of telescoping parts adjustably fixable with respect to one another, and means for operating the two aforementioned means simultaneously for joint adjustment of front and rear gangs.

4. In a harrow comprising a pair of front gangs, a front frame connected thereto, a pair of rear gangs, a rear frame connected thereto, the combination therewith of means connecting a frame and the front gangs for adjusting both front gangs jointly, means connecting a frame and the rear gangs for adjusting both rear gangs simultaneously, said means including a pair of telescoping parts adjustably fixable with respect to one another, and means for operating the two aforementioned means simultaneously for joint adjustment of front and rear gangs.

5. In a harrow comprising a pair of front gangs, a front frame connected thereto, a pair of rear gangs, a rear frame connected thereto, the combination therewith of means connecting the front frame and front gangs for angling the front gangs, means connecting the rear gangs and the front frame for angling the rear gangs, said means comprising telescoping parts adjustably fixable with respect to one another, and means for operating the two aforementioned means simultaneously for simultaneous adjustment of front and rear gangs.

6. In a harrow comprising a pair of front gangs, a front frame connected thereto, a pair of rear gangs, a rear frame connected thereto, the combination therewith of a lever mounted on the front frame, means connecting the lever and the front gangs, means connecting the lever and the rear gangs including telescoping parts adjustably fixable with respect to one another, and means for moving the lever angularly for effecting joint adjustment of front and rear gangs.

7. In a harrow comprising a pair of front gangs, a front frame connected thereto, a pair of rear gangs, a rear frame connected thereto, the combination therewith of a vertically extending lever mounted between its ends on the front frame, means connecting the lower end of the lever and the front gangs, means connecting the upper end of the lever and the rear gangs including telescoping parts adjustably fixable with respect to one another, and means for moving the lever angularly for effecting joint adjustment of front and rear gangs.

8. The combination specified in claim 7, and further comprising means mounted on the upper end of the lever for fixing the telescoping parts against relative movement.

9. The combination specified in claim 7, and further comprising a nut connected with one

telescoping part, and a rotatable crank connected with the other telescoping part and having threaded engagement with the nut.

10. In a harrow comprising a pair of front gangs, a front frame connected thereto, a pair of rear gangs, a rear frame connected thereto, the combination therewith of a vertically extending lever pivotally mounted between its ends on the front frame, means connecting the lower end of the lever and the front gangs, means connecting the upper end of the lever and the rear gangs comprising a tube connected with the rear gangs and a rod extending into the tube and connected with the upper end of the lever, a nut connected with the tube, a rotatable crank supported by the rod and the upper end of the lever and having threaded engagement with the nut, and means for moving the lever angularly for joint adjustment of front and rear gangs.

11. In a harrow comprising a pair of front gangs, a front frame connected thereto, a pair of rear gangs, a rear frame connected thereto, the combination therewith of a vertically extending lever pivotally mounted between its ends on the front frame, means connecting the lower end of the lever and the front gangs, means connecting the upper end of the lever and the rear gangs comprising a tube connected with the rear gangs and a rod extending into the tube and connected with the upper end of the lever, a second lever mounted adjacent the connection of the aforementioned lever and the rod, a link connecting the second lever and the sleeve, and means for moving the said aforementioned lever angularly for effecting joint adjustment of front and rear gangs.

12. In a harrow comprising a pair of front gangs a front frame connected thereto, a pair of rear gangs, a rear frame connected thereto, the combination therewith of a vertically extending lever pivotally mounted between its ends on the front frame, means connecting the lower end of the lever and the front gangs, means con-

necting the upper end of the lever and the rear gangs comprising a tube connected with the rear gangs and a rod extending into the tube and connected within the upper end of the lever, an arcuate toothed segment mounted adjacent the connection of the lever and the rod, a second lever pivotally mounted for angular movement with respect to the aforementioned lever and being fixable in a plurality of angular positions by means of the arcuate segment, and means for moving the first-mentioned lever angularly for effecting joint adjustment of front and rear gangs.

13. In a harrow comprising a pair of front gangs, a frame connected thereto, a pair of rear gangs, a rear frame connected thereto, adjusting means mounted on the front frame, means connecting the front gangs and the adjusting means, the combination with the adjusting means of means connecting the adjusting means and the rear gangs and comprising parts connected for relative sliding movement and stop means connected with one part for limiting relative movement between the parts in one direction and removable for causing the front gangs to operate in angled working position with the rear gangs in straight transport position.

14. In a harrow comprising a pair of front gangs, a front frame connected thereto, a pair of rear gangs, a rear frame connected thereto, the combination therewith of a vertically extending lever mounted between its ends on the front frame, means connecting the lower end of the lever and the front gangs, means connecting the upper end of the lever and the rear gangs including parts adjustably connected to one another for relative sliding movement, stop means connected with one part for limiting the relative sliding movement in one direction and being removable for causing the front gangs to operate in working position with the rear gangs in straight or transport position.

STEPHEN M. YOUNG.
